(57) **CLAIM**

The ornamental design for a lighting control panel, as shown and described.

DESCRIPTION

FIG. 1 is a top plan view of a lighting control panel showing our new design;

FIG. 2 is a front elevational view thereof;

FIG. 3 is a bottom plan view thereof;

FIG. 4 is a left side elevational view thereof;

FIG. 5 is a right side elevational view thereof;

FIG. 6 is a bottom, front, and left side perspective view thereof;

FIG. 7 is an enlarged and inverted top, front, and right side perspective view of the pair of buttons of the lighting control panel, with the remaining elements omitted for clarity of illustration;

FIG. 8 is an enlarged bottom, front, and left side perspective view of the pair of buttons;

FIG. 9 is a further enlarged front elevational view of the lower of the two buttons, with the remaining elements omitted for clarity of illustration;

FIG. 10 is a further enlarged left side elevational view of the lower of the two buttons;

FIG. 11 is a further enlarged right side elevational view of the lower of the two buttons; and,

FIG. 12 is a further enlarged vertical cross-sectional view of the lower of the two buttons, taken along the line 12—12 of FIG. 9.

The broken-line disclosure of various elements in the views is for illustrative purposes only and forms no part of the claimed design.
